METHOD AND MACHINE FOR MAKING
CUSHION PADSGeorge A. Gerard, Reading, Mass., assignor to
Cotton-Wood Products, Inc., Reading, Mass., a
corporation of MassachusettsApplication November 10, 1931, Serial No. 574,067
Renewed August 4, 1934

22 Claims. (Cl. 154—33)

The present invention relates to a method and machine for making cushion pads.

The object of the present invention is to provide a method and machine for making cushion pads of any desired shape, more particularly for making pads of circular, oval, or other non-rectangular shape.

With this object in view, the principal feature of the invention contemplates forming a bat of fibrous material, trimming the bat to the desired shape, delivering the bat between sheets of fabric, adhering the fabric sheets around the peripheral edge of the bat, and cutting the sheets beyond the edge of the bat. Although fibrous material of any suitable form may be used, it is preferred to employ the disintegrated paper described in the copending application of Gerard and Weisman, Serial No. 276,303, filed May 9, 1928. This material comprises waste paper containing both partially and completely disintegrated particles and, as explained in said application, the material is of great value, not only because of its capacity for retaining its form, but also because of its cheapness, its resiliency, and its heat insulating properties.

Other features of the invention consist of certain novel modes of operation and combinations and arrangements of parts hereinafter described and particularly defined in the claims.

In the accompanying drawings, Fig. 1 is an elevation partly in section of the preferred form of machine for practising the present invention; Fig. 2 is a plan view, partly in section; Fig. 3 is a section on line 3—3 of Fig. 2, of the bat forming roll; Figs. 4 and 5 are top and bottom plan views of the knife roll; Figs. 6 and 7 are top and bottom plan views of the sealing roll; Fig. 8 is a plan view of the bat forming roll; Fig. 9 is a section on line 9—9 of Fig. 3; Fig. 10 is a section on line 10—10 of Fig. 8; Fig. 11 is a section on line 11—11 of Fig. 7; and Fig. 12 is a section on line 12—12 of Fig. 5.

The machine illustrated in the drawings comprises a hopper 8 containing a supply of fibrous material, preferably a mixture of the partially and completely disintegrated paper fibers described in the copending application above referred to. Fiber particles are continuously fed from the hopper to a traveling apron 10 which preferably comprises one of the sheets for ultimately enclosing the bat. The paper is fed from the roll 12 over a roller 14, and passes over a table 16 lying under the hopper. The fiber deposited on the paper passes under a guard roll 18 and is lightly compressed into a bat by passing between positively

driven rolls 20 and 22. The continuous bat thus formed is delivered from between the rolls 20 and 22 to a ledge 24 which lies ahead of the bat forming roll 25. The paper 10 is removed from engagement with the bat prior to its delivery to the ledge 24, being carried around the lower roll 22 and downwardly around rolls 126 and 128.

The bat delivered from the ledge 24 is now shaped by the forming roll 25. This roll comprises a cylinder of wood, as shown in Fig. 8, 10 having an outer surface 26 which, if developed into a plane, is the shape of the desired bat. As shown in Fig. 2, the completed pad, indicated at 27, is of substantially circular shape. In this figure, the outer line indicates the peripheral edge of the pad and the inner line indicates the inner sealed edge of the pad, which corresponds to the shape of the bat itself. It will be noted that the pad 27 is not exactly circular but has a pointed end 28 for the purpose to be 20 presently described. Accordingly, the surface 26 of the forming roll is shaped to produce a substantially circular periphery of the bat except at the pointed end portions 28. The cylinder is 25 hollow, as indicated at 29, and is mounted on a shaft 30 driven from the drive shaft 31 by a sprocket chain 32. As the bat passes over the roll 25, its edges are trimmed by blasts of air directed against the edges of the roll. To this end, a pair of nozzles 33, operated in synchronism, are provided. Each nozzle 33 is connected with an air tube 34. Each nozzle is mounted in the end of a slide bar 35 which reciprocates in guides 36. Each bar has at its end a cam follower roll 37 engaged by a cam 38 mounted 35 on a shaft 40 and driven by beveled gears 41 from the shaft 30. The cams are constructed so that upon rotation of the cylinder, the air blasts follow and are directed against the edge of the surface 26. These blasts continuously trim off the bat as its point of support on the forming roll changes during the feed. The waste material falls into a hopper 42 which is connected with a suction pipe 45 for conveying the material back to the main feed hopper 8.

The formed bat leaving the roll 25 is delivered onto a ledge 43 and thence onto the sheet of paper 10 which loops back from the roll 128 and passes over a guide rod 44 adjacent to the ledge 43. It will be noted that the paper 10 50 loops completely around the hopper 42.

At this point, a second sheet of paper 48, which forms the upper sheet of the pad, is delivered from a roll 50 and passes under a roll 52 and over a roll 54, thence to pass to a roll 56 ar- 55

ranged immediately above the bat at the point where the latter is again deposited on the lower sheet 10. In its passage over the roll 54, the upper sheet is supplied with glue or other adhesive. The supply of glue is contained in a trough 58 from which the glue is delivered by continuously rotating rolls 60 and 62 to a glue roll 64. This glue roll is preferably provided with small protruding surfaces, as described in the copending application of Gerard, filed of even date herewith, in order that the glue may be applied to the sheet over small areas rather than over continuous surfaces, thereby permitting crumpling or twisting of the finished product without cracking of the glue or the paper.

The sheets 10 and 48, which meet under the roll 56, are passed over a table 66 to be engaged by a compression cylinder or sealing roll 68. It will be noted that the roll 56 is spaced a slight distance above the table 66, and that the sheets converge together as the sealing roll is approached, thereby providing sufficient adhering contact between the upper sheet and the bat itself. The cylinder 68 is in the form shown in Figs. 6 and 7, having a wooden core and a protruding rubber surface piece 70 which is complementary to the surface 26 of the bat forming roll. The roll 68 is driven in synchronism with the bat forming cylinder and the surface 70 engages with the sheet around the peripheral edge of the bat, thereby forcing the upper and lower sheets into engagement and causing them to adhere. The roll 68 cooperates with a smooth roll 72 which extends through a slot in the table 66 to engage the under sheet 10. It will be seen that the roll 68 compresses the outer marginal portions of the pad, but does not compress the fibrous material which adheres sufficiently well to the upper sheet without compression.

The material passing from the roll 68 therefore comprises a series of regularly spaced bats enclosed between the continuous sealed sheets 10 and 48. The pads are now delivered to a cutting roll 74 which severs the pads around the peripheral edges of the bats. The cutting roll includes the cylinder 74 to which is attached a knife 76 of the shape shown in Figs. 4 and 5. The shape of the knife 76 is such as to sever the pads 27. The knife, if developed into a plane, would be of the same shape as the developed surface 26 of the forming roll, but slightly larger, in order to leave a small marginal sheet area around the edge of the bat. The pads pass between the knife roll 74 and an under roll 78 which is supported at intervals upon wheels 80 freely journaled by roller bearings 82 on a shaft 84. The roll 78 and the supports 80 are of sufficient strength to resist the cutting pressure of the knife roll.

It will be noted in Fig. 5 that the knife edge has straight converging portions 86 to form the pointed ends 28 of the pad. If a true circular pad were constructed, the end portion of the knife would necessarily be of circular form tangent to one of the elements of the cylinder, that is to say, there would be a point at which the knife would make a purely transverse cut. It has been found that such a transverse cut requires a very considerable pressure on the roll 74, thereby rendering it difficult to afford sufficient support for the under roll 78. The pointed form of pad permits the knife to operate with a longitudinal cutting component at all times,

thereby diminishing the pressure necessary for the knife roll. If desired, a true circular pad or a pad of any other shape may be made, but for ordinary purposes, the pointed end is in no way objectionable and has the advantage of facilitating manufacture.

The completed pads are delivered from the knife roll over a ledge 90 to a traveling apron 92 from which they are discharged to be collected in any suitable manner. The waste material, namely, the portions of the sheet 10 and 48 surrounding the pads, may also progress over the apron and are discharged therefrom. Such waste material is not shown in Fig. 2.

The complete drive connections for the rolls 15 are not shown. The drive for the bat forming roll 25 is illustrated at 32, and similar drives for the rolls 20, 22, 68 and 74 are provided in order to permit operation thereof all in proper synchronization.

Having thus described the invention, what is claimed is:

1. A method of making a cushion pad which consists in forming a continuous bat of fibrous material, trimming the bat to a desired non-rectangular shape, placing the bat between fabric sheets, causing the fabric sheets to adhere around the peripheral edge of the bat, and cutting the sheets around the edge of the bat.

2. A method of making a cushion pad which consists in continuously forming a bat of fibrous material on a traveling apron, removing the apron from engagement with the bat, trimming the bat to a desired non-rectangular shape while out of engagement with the apron, continuously feeding sheets of fabric, delivering the trimmed bat between the sheets, adhering the sheets around the edge of the bat, and cutting the sheets beyond the edge of the bat.

3. A method of making a cushion pad which consists in continuously forming a bat of fibrous material on a traveling apron, removing the apron from engagement with the bat, trimming the bat while out of engagement with the apron over a surface of desired non-rectangular shape, removing the surplus material from the edge of the bat, continuously feeding sheets of fabric, delivering the trimmed bat between the sheets, adhering the sheets around the edge of the bat, and cutting the sheets beyond the edge of the bat.

4. A method of making a cushion pad which consists in continuously forming a bat of fibrous material on a traveling sheet of fabric, removing the sheet from engagement with the bat, trimming the bat to a desired non-rectangular shape, replacing the trimmed bat on the sheet, feeding another sheet on the opposite side of the bat, and adhering the sheets together.

5. A method of making a cushion pad which consists in forming a continuous bat on a traveling sheet of fabric, removing the sheet from beneath the bat and restoring engagement of the sheet with the bat at an advanced position, trimming the bat to a desired shape while out of engagement with the sheet, and feeding another sheet to engage the opposite side of the bat.

6. A method of making a cushion pad which consists in forming a continuous bat on a traveling sheet of fabric, removing the sheet from beneath the bat and restoring engagement of the sheet with the bat at an advanced position, trimming the bat to a desired shape while out of engagement with the sheet by supporting a portion of the bat and delivering a blast of air 75

- against the edge of the supported portion, and enclosing the trimmed bat between said sheet and another sheet, and cutting the sheets beyond the periphery of the bat.
- 5 7. A machine for making non-rectangular cushion pads having, in combination, means for forming a continuous bat, means for supporting a portion of the bat, means for trimming unsupported parts of the bat, said means being variable transversely of the bat to remove variable amounts of material therefrom, means for feeding the formed bat between two sheets of fabric, means for sealing the fabric around the bat, and means for cutting the fabric.
- 10 8. A machine for making cushion pads having, in combination, means for forming a continuous bat, a cylinder over which the bat is passed, the cylinder having a surface of the desired shape of the bat when developed, means for removing waste material from around the edges of the cylinder, means for feeding the formed bat between two sheets of fabric, means for sealing the fabric around the bat, and means for cutting the fabric.
- 15 9. A machine for making cushion pads having, in combination, means for forming a continuous bat, air blast means for trimming the bat to a desired non-rectangular shape, said means being variable transversely of the bat to remove variable amounts of material therefrom, means for feeding the formed bat between two sheets of fabric, means for sealing the fabric around the bat, and means for cutting the fabric.
- 20 10. A machine for making cushion pads having, in combination, means for forming a continuous bat, means for supporting the bat, air blast means for trimming the bat in accordance with the contour of the supporting means, means for feeding the formed bat between two sheets of fabric, means for sealing the fabric around the bat, and means for cutting the fabric.
- 25 11. A machine for making cushion pads having, in combination, means for forming a continuous bat, bat supporting means, means for trimming the bat during its passage over the supporting means, said trimming means being variable transversely of the bat to remove variable amounts of material therefrom, means for placing the trimmed bat between sheets of fabric, a sealing roll having a surface complementary to that of the supporting means, and means for cutting the sheets.
- 30 12. In a machine for making cushion pads, a rotary knife having a cutting edge to cut on a curved contour, and converging end portions to produce a longitudinal cutting component at all points without a transverse cut at any point.
- 35 13. In a machine for making cushion pads, a knife roll, a knife disposed on the roll to cut on a curved periphery, and having converging straight end portions to produce a longitudinal component of cutting at all points without a transverse cut at any point.
- 40 14. A machine for making cushion pads having, in combination, means for forming a continuous bat, means for feeding the bat, a rotating support over which the bat is fed, the support having a surface of the desired shape of the bat, means for trimming the bat while being fed over the support, and means for feeding the bat to a sheet of fabric.
- 45 15. A machine for making cushion pads having, in combination, means for forming a continuous bat, means for feeding the bat, a rotating cylinder over which the bat is fed, the cylinder having a developed surface of the desired shape of the bat, trimming means for directing a blast of air against the cylinder to trim the bat, and means for feeding sheets of fabric between which the trimmed bat is fed.
- 50 16. A machine for making cushion pads having, in combination, means for forming a continuous bat, means for feeding the bat, a support over which the bat is fed, the support having a surface of the desired contour of the bat, trimming means for removing the surplus material from the edge of the support, and means for moving the trimming means to accommodate the shape of the support.
- 55 17. A machine for making cushion pads having, in combination, means for forming a continuous bat, means for feeding the bat, a rotating support over which the bat is fed, the support having a surface of the desired shape of the bat, means for trimming the bat while being fed over the support, means for moving the trimming means in synchronism with the support, and means for feeding the bat to a sheet of fabric.
- 60 18. A machine for making cushion pads having, in combination, means for forming a continuous bat, means for feeding the bat, a rotating cylinder over which the bat is fed, the cylinder having a developed surface of the desired shape of the bat, trimming means for directing a blast of air against the cylinder to trim the bat, means for moving the trimming means in synchronism with the support, and means for feeding sheets of fabric between which the trimmed bat is fed.
- 65 19. A machine for making cushion pads having, in combination, means for forming a continuous bat, means for supporting a portion of the bat, means for trimming unsupported parts of the bat, means for feeding the formed bat between two sheets of fabric, means for sealing the fabric around the bat comprising a sealing roll having a sealing surface conforming to the periphery of the bat, and means for cutting the fabric.
- 70 20. A machine for making cushion pads having, in combination, means for forming a continuous bat, a cylinder over which the bat is passed, the cylinder having a surface of the desired shape of the bat when developed, means for removing waste material from around the edges of the cylinder, means for feeding the formed bat between two sheets of fabric, means for sealing the fabric around the bat comprising a sealing roll having a sealing surface conforming to the periphery of the bat, and means for cutting the fabric.
- 75 21. A method of making a cushion pad which consists in forming a continuous bat of fibrous material, directing jets of air against the bat to remove variable amounts of material therefrom to trim the bat to non-rectangular shape, placing the bat between fabric sheets, causing the fabric sheets to adhere around the peripheral edge of the bat, and cutting the sheets around the edge of the bat.
- 80 22. A machine for making cushion pads having, in combination, means for forming a continuous bat, means for feeding the bat, a support over which the bat is fed, an air jet for removing portions of the bat, means for operating the jet to remove more material adjacent the edges than at the center to trim the bat to non-rectangular shape, means for enclosing the bat between fabric sheets, and means for cutting the sheets around the periphery of the bat.

GEORGE A. GERARD.
